UNITED STATES PATENT OFFICE.

C. AXEL BACKSTROM, OF TRENTON, NEW JERSEY, ASSIGNOR TO THE BACKSTROM CENTRIFUGAL SEPARATOR COMPANY, OF NEW JERSEY.

CENTRIFUGAL LIQUID-SEPARATOR.

SPECIFICATION forming part of Letters Patent No. 368,047, dated August 9, 1887.

Application filed March 2, 1887. Serial No. 229,426. (No model.)

To all whom it may concern:

Be it known that I, C. AXEL BACKSTROM, a citizen of the United States, residing at Trenton, in the county of Mercer, State of New Jersey, have invented certain new and useful Improvements in Centrifugal Liquid-Separators, of which the following is a specification, reference being had therein to the accompanying drawings.

- 10 This invention has relation to centrifugal liquid-separators, and among the objects of the invention are to construct a machine so that it may be supported from a point above, and while so supported may automatically, when 15 in operation, assume its true center of gravity and the bowl thereof find and retain its true center of motion. The construction of the frame-work, the devices for suspending the same, the form of the bowl, the devices for rotatively supporting the same, and suitable 20 supply and delivery devices for the liquid to be separated and for its separated constituents are matters also included in the object of the invention.
- 25 Other objects and advantages of the invention will appear in the following description, and the novel features thereof will be particularly pointed out in the claims.

My invention is applicable to all centrifugal 30 liquid-separators, and to a use thereof in separating all liquids, semi-liquids, and other substances made up of constituents having different degrees of specific gravity, and which are capable of separation by the employment of 35 centrifugal force. In this instance I shall illustrate the mode of operation of my invention in a description of its use in the separation of cream from milk; but, as before indicated, I do not limit the invention to any particular 40 use thereof.

Referring to the drawings, Figure 1 is a side elevation, Fig. 2 a central vertical section, Fig. 3 a horizontal section on the line X-X of Fig. 2, and Fig. 4 a plan, of a centrifugal liquid-separator embodying my invention.

Like letters indicate like parts in all the figures.

A represents a frame-work, which consists of a main portion, which is oblong and provided at the center of one side with a hub or

boss, A', for the reception of a bowl-supporting step or stud, B, and at its opposite side said frame-work is extended in open form and provided with a boss, A'', for the reception of a fixed non-rotative shaft, C. Each of the portions of the frame-work constituting the open extension is provided with a boss or hub, A³, which is countersunk, as at A⁴, for the reception of a bearing pin, screw, or bolt, A⁵, which is mounted in the ring D.

E is a yoke, which, by pivot pins, screws, or bolts E', is pivotally connected to the ring D at points diametrically opposite each other and midway between the pivots A⁵ in the ring D. The yoke and the ring constitute, when in operation, the well-known concentric ring or compass support, which, when the yoke is supported by the swivel-hook E', permits of an oscillation or movement of the frame A in all directions, so that it and the parts mounted 65 therein will, as a whole, naturally assume a position agreeing with the center of gravity of the entire structure.

F represents the bowl of the machine, and in this instance it is formed with an opening 75 in its bottom which embraces the stud B. It is also provided with an upper annular supply-chamber, F', and a lower annular chamber, F''. Above and upon the upper annular chamber there is formed a hub, F³, which embraces and takes bearing upon the non-rotative 80 shaft C.

Within the bowl and depending from the center thereof is a convex-ended hard steel or other suitable pin, G, which supports the bowl 85 by resting upon a similar pin, G', seated in the bottom of an oil-cup, B', formed on the upper end of the stud B. A pulley, H, is mounted for rotation upon the stationary shaft C, and has at one end a clutch-lug, H', (see Fig. 90 1,) which takes into a notch, H'', formed in the upper edge of the hub of the drum, whereby the pulley may be disconnected from the drum by moving the former vertically upon the shaft C. An oil-cup, C', formed in the top of the 95 shaft, serves the purpose of storing a lubricant, which is conducted to the bearings of the pulley and bowl through a groove, C''. A milk-supply-conducting passage, C³, is formed in the stationary shaft and communicates with 100

the supply-chamber F' of the bowl. The bowl F is in this instance provided with a series of vertical blades with or without annular shelves, and one, F⁴, of which blades is imperforate, 5 while the remaining blades of the series are provided with ports which permit of the passage of a liquid to be separated from one to the other of the compartments formed by the blades.

10 A detailed description of the construction and arrangement of the blades and shelves may be found by reference to United States patents granted me, and dated December 28, 1886, and numbered 355,049 and 355,050.

15 A supply-pipe, F¹, (see dotted lines, Fig. 2,) extends from the annular chamber F' and into the bowl and near its inner periphery, and a discharge-pipe, F⁶, is arranged at an opposite side of the imperforate blade F⁴ and extends 20 from said inner periphery to the annular chamber F². The step or stud B is bored longitudinally to form delivery-passages B² B³, the latter being shown by dotted lines, Fig. 2. Lateral 25 passages B⁴ B⁵ are formed at the upper ends of the passages B² B³, respectively, and through projections B⁶ B⁷, formed on or attached to the stud. At or near the lower ends of the passages B² B³ there are formed lateral 30 passages B⁸ B⁹, which communicate with discharge-pipes B¹⁰ B¹¹, each having a controlling-valve, I J, respectively. The stud B projects through and below the frame A, as clearly shown, whereby the controlling-valves on the discharge-pipes are readily accessible.

35 A machine of the class described, which is constructed substantially as above detailed, will secure the principal and subsidiary objects of my invention, and its operation will be substantially as follows: A belt running 40 from any prime motor and in connection with the pulley H will, when said pulley has connection with the bowl, as described, cause the bowl to rotate while supported on the pins G G' and take a bearing upon the non-rotative shaft C. A suitable supply of liquid to 45

be separated into its constituents—for example, milk—is introduced through the passage C³ from any suitable tank, and said supply, being controlled, if desired, by a valve arranged 50 in the pipe leading from the tank—for example, as shown by dotted lines, Fig. 2—will be delivered from the chamber F' through the pipe F⁵ into the bowl at one side of the imperforate blade. After passing around the bowl 55

the milk, when it arrives at the opposite side of said blade, will pass through the pipe F⁶ into the annular chamber F². The cream, which naturally collects in an annular body nearer the center of motion, will be discharged from 60 the machine by means of the projection B⁶ and the passage B⁴ therein, together with the communicating-passages B² B³ and the discharge-pipe B¹⁰. The skimmed milk will in like manner be conducted from the annular compartment of the bowl by means of the projection B⁷ and the passages B³ B⁵ B⁹ and discharge-pipe B¹¹. 65

I have discovered that by controlling the delivery of the constituents after they have been separated from each other I can determine their character or quality. By permitting a perfectly free discharge of the heavier constituent, and, if desired, a rather increased quantity of the same over and above its normal proportion, I can control the quality of the lighter constituent, so as to render it more or less free from the presence of any of the heavier constituents. So, also, by a proper control of the discharge of both constituents I can vary the quality of each, in that each will be more or less impregnated with the other. It is essential in such a control of the delivery of the constituents that the delivery devices shall have a continuous unbroken communication and shall extend from the points within the bowl at which the separate constituents naturally collect during the operation of the machine to points outside of the bowl, and it is also essential that such delivering devices shall be fixed as compared with the bowl, which is movable, in order that the specified control can be exercised while the machine is in operation.

I do not herein broadly claim the delivery devices *per se*, as the same are described, shown, and claimed in a companion application pending herewith.

To resume the operation of the machine, it will be seen that the cream will be conducted from the machine through the passages communicating with the discharge-pipe B¹⁰, while the milk will be conducted through the passages communicating with the discharge-pipe B¹¹, and that the quantity of each constituent discharged may be readily controlled by the valves I and J, respectively, while the machine is in operation.

It is apparent that the bowl F may be supported rotatably upon the non-rotative shaft C by means of any suitable burr or nut, K, or its equivalent, arranged at the lower end of the shaft so as to bear upon the upper inner surface of the annular chamber F', as shown by dotted lines, Fig. 2. In such case the bottom of said annular chamber would be removably secured by screw-threading, as shown at L, or otherwise, and the upper end of the stud B would be removed, so that the supporting-pins G G' and oil-cup B' would be dispensed with.

So far as the frame-work and the manner of connecting the bowl with the same are concerned, it is apparent that the interior construction of the bowl and the delivery devices employed therewith may be essentially different from those shown and described, and I therefore do not limit my invention in these particulars.

What I claim is—

1. The combination, with the separating-bowl of a centrifugal machine having a depending receptacle and a discharge-pipe communicating therewith and with the interior of the bowl, of a non-rotative stud projecting

upwardly into the bowl and bored to form delivery-passages, one of which communicates with the depending receptacle and the other with the interior of the bowl, and each provided with a controlling valve or cock substantially as specified. 5

2. In a centrifugal machine, a bowl provided with an imperforate blade, an upper supply-chamber and a pipe projecting therefrom at one side of said blade, and a lower discharge-receptacle and a pipe projecting within the bowl and at an opposite side of said blade, and a non-rotative stud or step bored to form discharge-passages, one of which communicates with the interior of the bowl and the other with the discharge-receptacle, substantially as specified. 15

3. In a centrifugal machine, a bowl provided with an imperforate blade, an upper supply-chamber and a pipe projecting therefrom at one side of said blade, and a lower discharge-receptacle and a pipe projecting within the bowl at an opposite side of said blade, and a non-rotative stud or step bored to form discharge-passages, one of which communicates with the interior of the bowl and the other with the discharge-receptacle, and each provided with a controlling cock or valve, substantially as specified. 25

30 4. The combination, with the bowl of a cen-

trifugal machine, of a frame-work having a non-rotatable shaft and a non-rotatable stud or step, each arranged in line with the other, the bowl supported for rotation upon the shaft, and concentric rings, substantially as specified. 35

5. In a centrifugal machine, and in combination with the bowl thereof, a stationary bowl-supporting stud provided with discharge-passages communicating with the interior portions of the bowl, and provided with controlling valves or cocks secured in the stud to communicate with the passages thereof, and bearing-points carried by the stud and bowl, substantially as specified. 40

6. The combination of the frame A, having the stud B and shaft C, with the bowl F, the ring D, and yoke E, substantially as specified. 45

7. The combination of the frame A, having the stud B, provided with the passages B² B⁴ B⁸, the bowl F, supported by the stud, the shaft C, and the pulley H, detachably connected with the bowl, substantially as specified. 50

In testimony whereof I affix my signature in presence of two witnesses.

C. AXEL BACKSTROM.
